much diversity in the way of architectural detail in the
surrounding hill country. The chief object of the late Mr. John
H. Johnson, of San Antonio, was to collect
specimens of the various forms of architecture
existing in the country, and to have them
represented in a series of photographs, which
he intended to publish in a volume of
illustrations. He died before his work
was completed, and the collection
was left to the care of his
son, Mr. W. H. Johnson, who
is now engaged in
the preparation of the
volume.

UNITED STATES PATENT OFFICE

2,421,989

MACHINE FOR HARDENING GEARS

George H. Bryan, Brighton, N. Y., assignor to
Gleason Works, Rochester, N. Y., a corporation
of New York

Application February 19, 1944, Serial No. 523,081

2 Claims. (Cl. 266—23)

1

The present invention relates to machines for surface-hardening gear teeth and particularly to machines for the localized hardening of the teeth of spiral bevel and hypoid gears in which heating elements, such as oxy-acetylene torches, are moved longitudinally of the teeth to bring the teeth up to the required hardening temperature for hardening by subsequent quenching or air-cooling. In a more specific aspect, the invention constitutes an improvement on the surface-hardening machine of the Slade patent, No. 2,102,040, issued December 14, 1937.

The machine of the Slade patent and the most generally used types of machines for surface-hardening bevel gears by the flame-hardening process carry two torches, and these torches are moved simultaneously along opposite sides of a gear tooth to treat both sides of the tooth simultaneously. In the machine illustrated in the Slade patent, the two torches are mounted in a pair of blocks that have transverse sliding movement in a reciprocable ram or slide. The ram or slide is reciprocated to move the torches along opposite sides of a gear tooth from end to end, while the blocks are movable transversely toward and from one another, during movement of the ram, so that each torch may be maintained at a constant distance from the side of the tooth, on which it is operating, as it moves from one end of the tooth to the other. The transverse movements of the blocks are controlled by two cam rails that are adjustably mounted on the base of the machine and that are shaped and positioned to maintain the uniform distance between the torches and tooth sides during the movements of the ram.

A primary object of this invention is to provide a surface-hardening machine having a more rigid support for the torches than machines heretofore built.

A further object of the invention is to provide a surface-hardening machine on which the torches are so mounted that they may move easily and smoothly toward and from one another as they travel from one end of a tooth to the other, so that sticking or binding of the torch carriers will be eliminated.

Other objects of the invention will be apparent hereinafter from the specification and from the recital of the appended claims.

In the drawings:

Fig. 1 is a plan view of the torch end of a surface-hardening machine built according to a preferred embodiment of this invention;

Fig. 2 is a side elevational view of this part of the machine:

Fig. 3 is a fragmentary plan view on an enlarged scale, showing a detail of the torch mounting; and

Fig. 4 is a part end elevation and a part transverse sectional view of the torch mechanism.

In the modification illustrated in the accompanying drawings, the invention constitutes an improvement on the torch end of the machine of the Slade patent, and, since the rest of the machine may be of the same structure as shown in the Slade patent, it has not been deemed necessary to illustrate the rest of the machine.

In the drawings, 10 (Fig. 4) denotes a support or base which may be of the same structure as the cylinder 82 of the Slade patent. Pivottally mounted on this base or support 10, as by means of the trunnion 11, is a supporting bracket 12 which serves to carry the torches and their operating parts. The supporting bracket 12, like the supporting bracket 76 of the Slade machine, may be adjusted angularly about the axis of the trunnion 11, to position the torches in the correct angular relation to the work in accordance with the root angle of the work. Mounted in the bracket 12 is a cylinder 14 (Fig. 2) in which the piston 15 is reciprocal. The piston is secured to a piston rod 16 that projects through one end wall of the cylinder and that is formed exteriorly of the cylinder with a rack 17. This rack meshes with a pinion 18 (Figs. 2 and 4) which is integral with a spur gear 20. The pinion 18 and spur gear 20 are journaled on the trunnion 11 by means of bushings 21. The gear 20 meshes with a rack 22 which is secured to a ram 23 by screws 24. The ram 23 reciprocates in a guide way 25 (Fig. 3) formed in the upper face of the bracket 12, and the ram is held in this guide way by the gibbs 26 (Figs. 1, 3, and 4).

45 Mounted on the ram 23 to pivot about the axis of a stud 30 are two arms 31 and 32. These arms are formed on their forward free ends with portions 33 and 34 (Fig. 3), respectively, that ride on the plane upper face of an enlarged forward end portion 35 of ram 23. The arms 31 and 32 terminate at their free forward ends in arcuate end surfaces 37 and 38, respectively, which are concentric with the stud 30. A gib 39, which 50 is secured by screws 40 to the head 35 of the ram engages over the terminal portions of the arms to prevent canting of the arms 31 and 32 in their rocking movements and to hold them down on the seat 35.

55 Mounted on the arms 31 and 32 and laterally

adjustable thereon are the blocks or anvils 41 and 42 (Figs. 1, 2, and 4), respectively. These may be adjusted laterally on the arms by screws 43 and 44, respectively, which are mounted in the arms 31 and 32, respectively, and which thread into the blocks 41 and 42, respectively. The blocks 41 and 42 are secured to the arms in any adjusted position by tightening up the handles 45 and 46, respectively, which engage with bolts that pass through slots in the blocks and that thread into the arms. Adjustment of the blocks 41 and 42 serves to control the distance between the torches in accordance with the pitch of the gear to be treated.

Mounted on the blocks 41 and 42 and longitudinally adjustable thereon are bars or rails 49 and 50, respectively. These bars or rails are secured to the blocks by T-bolts 51 (Fig. 4) which engage in slots formed in the bottoms of the bars and which are moved to and from clamping position by the operating handles 53 and 54, respectively. Pivoted mounted on the forward ends of the bars 49 and 50 by means of hinge pins 55 and 56, respectively, are rocker arms 57 and 58, respectively. Pipes 59 and 60, respectively, are secured to these arms. To these pipes are fastened the torch tips 61 and 62, respectively.

The rocker arms 57 and 58 carry adjustable stop-screws 68 which are adapted to engage lugs 78 and 78', respectively, that are formed on the bars 49 and 50, respectively. Through adjustment of the screws 68 and 68', the torches can be positioned more precisely, in accordance with the root angle of the work, and the angular adjustment of the supporting bracket 12 on the trunnion 11 is only a more or less rough adjustment. When the rocker arms 57 and 58 are swung upwardly about their pivots, the torches are moved clear of the work to permit ready access to the work.

The torches 61 and 62 may be of any usual or suitable construction. The oxy-acetylene gas is supplied to the pipes 59 and 60, respectively, through flexible tubing 63 and 64 which connects with a manifold 65 (Fig. 1) that in turn is connected through tubing 66 with a mixing chamber 67 to which oxygen and acetylene gases are conducted through tubing 69 (Fig. 2). The mixing chamber 67 is supported by a block 70 from the ram 23. The height of the torches can be adjusted by manipulating the knurled nuts 71 and 72, respectively, which thread onto the pipes 59 and 60, respectively, and which seat against the upper faces of the arms 57 and 58, respectively. After the torches have been adjusted for height, they may be secured in adjusted positions by clamping bolts which are manipulated by handles 73 and 74.

The arms 31 and 32 are constantly urged away from one another by the coil springs 75 and 76 (Fig. 3), respectively, which are housed in holes drilled in the arms and which seat against a pin 77 that is secured in the ram 23. The arms carry rollers 79 and 80, respectively, which ride on cam rails 81 and 82, respectively, as the ram 23 reciprocates.

The active surfaces 83 and 84, respectively, of the cam rails are shaped in accordance with the lengthwise tooth shape of the gear to be hardened. In the embodiment illustrated, the active surface 83 of the cam rail 81 is of concave lengthwise shape and the active surface 84 of the cam rail 82 is of convex lengthwise shape so that the torches may follow the lengthwise shapes of opposite sides of a tooth T (Fig. 1) of a longitudinally curved toothed gear of zero spiral angle,

that is to be hardened, as the torches move from one end of the tooth to the other in the reciprocation of the ram 23.

The cam rails 81 and 82 are clamped to the upper face of the bracket 12 by clamping plates 85 and 86, respectively. These plates are secured in position by bolts that pass through elongated slots 87 and 88, respectively, formed in the cam rails and that thread into the bracket 12. These bolts may be manipulated by the hand levers 89. For hardening bevel gears, the cam rails are adjusted angularly with reference to one another so that the torches will converge as they move from the large to the small end of a tooth of the gear being hardened. For the purposes of this adjustment, the cam rails are graduated at one end, as clearly shown in Figs. 1 and 3, to read against zero marks inscribed on blocks 90 and 91, respectively. These blocks are integral with the bracket 12 and extend from the upper face thereof. In Fig. 1, the cam rails are shown inclined to one another in the positions which they might occupy when the torches are to move from the large to the small end of a gear tooth on the forward stroke of the ram, while in Fig. 3 the cam rails are shown inclined to one another in the positions which they might occupy when the torches are to move on the forward stroke of the ram from the small to the large end of a pinion tooth.

The means for actuating the ram 23 and for controlling the speed and direction of its movements may be similar to those disclosed in the Slade patent and form no part of the present invention.

Thus, the direction of movement of the ram 23, namely, the direction of movement of the piston 45, may be controlled by a reverse valve mounted in the valve casing 94 (Fig. 1). This valve may be operated in exactly the same manner as the reverse valve 101 of the Slade patent above mentioned. It may be moved in one direction by a hand lever 95 and in the opposite direction through operation of a trip lug 96 and lock dogs 97. The trip lug 96 is mounted on the upper face of the ram 23 and is adjustable longitudinally thereof. It may be secured in any adjusted position by means of a bolt 98 which engages in an elongated slot 98' that is provided in the face of the ram. A scale 99 is secured to the upper face of the ram adjacent to the slot 98' to permit of positioning the trip lug precisely.

The speed of movement of the ram may be controlled, as in the Slade patent, by a pair of throttle valves, such as the throttle valves 103 and 104 of the Slade patent. These valves may be mounted in a valve casing 100 that is secured to the upper face of the bracket 12. One of the valves may be operated by a bell-crank lever 102 which is pivoted at 103 on the upper face of the bracket 12 and which is connected through the rod 104 with the valve. The bell-crank lever carries a roller 105 which rides against a cam rail 106. The cam rail 106 is adjustably secured to a rail or bar 108 by a bolt, that passes through an elongated slot 107 in the rail 106 and that threads into the bar 108. Graduations on the rail or bar 108 permit of precisely adjusting the rail 106. The rail 106 may be clamped in any adjusted position by manipulating the handle 109 which is secured to the locking bolt.

The rail or bar 108 can be adjusted angularly on the ram 23 about a pivot pin 112. It may be secured in any adjusted position by a bolt that threads into the ram and that is manipulated by a handle 113. It may be positioned precisely

5

by the graduations on its upper face at its rear end, which read against a zero mark provided on a boss 110 that is integral with the ram 23. As the ram reciprocates, the roller 105 will ride on the rails 106 and 108 and the bell-crank lever 102 will be rocked about its pivot 103 causing the throttle valve, which is connected thereto, to vary the speed of movement of the piston 15. Knurled knobs 114 and 115 are provided for adjusting the two throttle valves that control the speed of movement of the ram.

From the preceding description, it will be seen that as the ram 23 is reciprocated on the bracket 12 by operation of the piston 15, rack 16, gears 18 and 20, and rack 22, the arms 31 and 32 will be moved toward or from one another, depending upon the direction of movement of the ram and the shapes and positions of the cam rails 81 and 82. Thus, the torches may be caused to move toward or away from one another as they move along the length of the tooth to be hardened. The construction of the arms 31 and 32 provides a very rigid support for the torches and the rocking movement of the arms assures easy control of their motions from the cam rails without sticking or binding. The cam rails 81 and 82 can, of course, be made of various shapes to suit the lengthwise tooth shapes of the gears to be hardened.

While the invention has been described in connection with a machine such as disclosed in the Slade patent, it will be understood that the features of the invention have other applications, also. Thus, the invention may be employed on a machine in which the work is not stationary during hardening but is rolled under the torches so that they may follow the spiral curvature of a tooth, as is the case in the machine of the Bullock et al. Patent No. 2,294,891, issued September 8, 1942. In general it may be said that while the invention has been described in connection with a particular embodiment thereof, it is capable of still further modification and this application is intended to cover any variations, uses, or adaptations of the invention following, in general, the principles of the invention and including such departures from the present disclosure as come within known or customary practice in the art to which the invention pertains and as may be applied to the essential features hereinbefore set forth and as fall within the scope of the invention or the limits of the appended claims.

Having thus described my invention, what I claim is:

1. In apparatus for hardening gears, a base, a ram reciprocable on the base, a pair of arms which are pivotally mounted at one of their ends on said ram for oscillation which extends trans-

6

versely of the direction of movement of the ram, a heating element carried by each arm at its free end, a pair of cam rails fixed to said base and extending in the general direction of movement of the ram, a follower carried by each of said arms intermediate its ends and engaging one of the cam rails, means for holding the followers against the cam rails whereby on movement of the ram, the arms and the heating elements carried thereby are oscillated, a supporting member having an arcuate guide surface secured to each arm intermediate its ends in position to ride on the ram as the arm swings, and an arcuate guide way on the ram with which the supporting members are engaged, the arcuate surfaces of the supporting members and guide way being curved about the pivot point of the arms as a center.

2. In apparatus for hardening gears, a base, a ram reciprocable on the base, a pair of arms which is pivotally mounted at one of their ends on said ram for oscillation about a common axis that extends in a direction transverse to the direction of movement of the ram, a heating element carried by each of said arms at the free end of said arm, a pair of cam rails fixedly secured to the base and extending in the general direction of movement of the ram, a follower carried by each of said arms intermediate its ends and engaging one of the cam rails, a spring interposed between the ram and each arm at a point between the follower and the arm's pivot and operative to hold each follower against the corresponding cam rail whereby on movement of the ram, the arms and heating elements carried thereby are oscillated, a supporting member having an arcuate guide surface secured to each arm at a point between the spring and the free end of the arm and mounted to ride on the ram as the arm swings, an arcuate guide way on the ram with which the supporting members engage, the arcuate surfaces of the supporting members and guide way being curved about the pivot point of the arms as a center.

GEORGE H. BRYAN.
